Joseph Rose of Broad Brook New Jersey
Letters Patent.

The Schedule is made to in these Letters Patent and making part of the same, containing a description in the words of the said Joseph Rose himself of his improvement in a Machine patented by himself on the 12th of April 1833. for the purpose of shelling corn by which improvement it is adapted to the threshing of grain.

To all whom it may concern. Be it known that I Joseph Rose of Broad Brook in the County of Hunterdon and State of New Jersey did on the 12th day of April 1833. obtain Letters Patent of the United States, for a machine for shelling corn. and that I have since discovered that by certain improvements or variations, thereon. I can adapt the same to the threshing of grain. my said improvement however being capable of being used as a threshing machine by applying the cylindrical body and concave herein described to any suitable frame other than that used with my shelling machine. the only motive for combining the two being the saving of expense.

I make that part which is usually denominat'd the cylinder in threshing machines smaller in the middle than at the ends. so that instead of being a cylinder it is in fact formed by the union of two truncated cones, at their smaller ends the difference of diameter between the middle and ends may be about one inch. I prefer not to make the difference greater as I can thus use a concave which is straight longitudinally whilst if the cylindrical part was made much smaller in the middle. it would be necessary to make the concave conform thereto. by giving it a rise in the centre. but I usually make the teeth driven into the cylinder to vary in length. so that their outer ends will in revolving pass each other at the same distance from the concave. I drive teeth into the cylindrical body which teeth project from an inch to an inch and a half. and also drive similar teeth into the concave. these may be square three eighths iron. I do not drive them straight but incline them in both in such a way as shall tend to prevent their breaking the straw then slope separating them readily therefrom. I usually cover the cylinder and concave with sheet iron as the teeth to render them more durable. In the form of my shelling machine this cylinder and concave may be substituted for the shelling apparatus. so that the

Drawing No. 1

one or the other may be used at pleasure, & I place this cylinder and concave in a suitable frame without reference to the shelling machine, in either case a proper feeding table or any other well known contrivance for that purpose may be used. The only thing which I claim as new is the form given to what is usually denominated the cylinder by making it smaller at the center than at the ends as herein described, the effect of which it has been experimentally proved to prevent that annoyance from from the current of wind and dust, produced in other machines for threshing grain. Although I have spoken of the receding body as formed by the union of two truncated cones, the effect will be similar if instead of using the double cone as described, the cylinder be made concave in a regular curve reducing the diameter in the middle, so that it shall be one inch or upwards less there than at the two ends. In testimony that the foregoing is a true description of my invention I have hereunto set my hand & day 23rd 1835.
